US00D838716S

(12) **United States Design Patent** (10) **Patent No.:** **US D838,716 S**
(45) **Date of Patent:** **** Jan. 22, 2019**

(54) **SMART WATCH**

(71) Applicant: **Lite-On Technology Corporation**,
Taipei (TW)

(72) Inventors: **Jun-Wen Teng**, Taipei (TW);
Chieh-Hung Chen, Taipei (TW)

(73) Assignee: **Lite-On Technology Corporation**,
Taipei (TW)

(**) Term: **15 Years**

(21) Appl. No.: **29/614,762**

(22) Filed: **Aug. 23, 2017**

(51) LOC (11) Cl. **14-02**

(57) **CLAIM**

The ornamental design for a smart watch, as shown and described.

DESCRIPTION

FIG. 1 is a perspective view of a smart watch showing our new design;

FIG. 2 is another perspective view thereof;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The dashed broken lines depict portions of smart watch that form no part of the claimed design.

1 Claim, 7 Drawing Sheets
